UNITED STATES PATENT OFFICE.

PETER J. JORGENSEN AND CLARENCE H. JORGENSEN, OF CHICAGO, ILLINOIS.

INTERNAL-COMBUSTION ENGINE.

Application filed June 12, 1925. Serial No. 36,588.

This invention relates to a new and improved device for controlling the richness of the fuel mixture passing to the cylinders of an internal combustion engine. The invention is particularly adapted for use in connection with automobiles. When the engine of an automobile is first started up the cylinders are cold, the temperature thereof depending upon the length of time the engine 10 has been idle. Under such conditions it is desirable to start the engine with a rich mixture and then to thin out the mixture after the engine has been in operation, the rich mixture being unnecessary after the cylinders 15 become heated. One of the purposes of our invention is to provide means for doing this and means for automatically thinning out the mixture after the engine is started.

The invention has as another object to prevent the thinning of the lubricating oils for the engine pistons and cylinders when a rich fuel is used in starting.

The invention has other objects which are more particularly pointed out in the following description.

Referring now to the drawings:

Fig. 1 is a view of one form of apparatus embodying the invention.

Fig. 2 is a side view of the indicating device associated with the control arm.

Fig. 3 is an enlarged plan view partly in section of the control valve and associated parts.

Fig. 4 is a vertical sectional view taken on line 4—4 of Fig. 3.

Fig. 5 is a vertical sectional view taken on line 5—5 of Fig. 3.

Fig. 6 is a view taken on line 6—6 of Fig. 5.

Fig. 7 is a sectional view taken on line 7—7 of Fig. 4. Fig. 7^a is a view of piston head of Fig. 4.

Fig. 8 is a plan view of the piston illustrated in Fig. 4.

Fig. 9 is a view showing a modified construction.

Fig. 10 is a view showing the valve controlling cylinders of Fig. 9 in section.

Fig. 11 is a sectional view showing a modified valve controlling cylinders.

Like numerals refer to like parts throughout the several figures.

Referring now to the drawings, we have illustrated in Fig. 1 an internal combustion engine having a series of cylinders 2 by means of which the engine shaft 3 is driven. These cylinders are provided with the ex-

haust 4 and the intake manifold 5. The carburetor 6 is connected with the pipe 7 leading to the engine cylinders. There is also connected with this pipe 7 an air intake pipe 8 through which air is drawn by the engine cylinders and which mixes with the fuel supply from the carburetor, the mixture passing through the manifold 5 to the engine cylinders. We prefer to heat this air in some suitable manner. In the construction shown we apply a heater 9 which surrounds the exhaust pipe 4 and which is connected with the air pipe 8, the air passing into the heater through the openings 10, being heated by the exhaust pipe, then passing through the air pipe 8. We provide a means for securing a rich mixture of fuel when the engine is started, and we provide an automatic means for changing this rich mixture when the engine is working properly so as to thin it out the desired amount. When a rich fuel mixture is injected into the cylinders and pass down into the crank case, and dilute the lubricating oil. Our invention prevents this. We provide a means for controlling the ratio between the air and the gasoline, thereby controlling the ratio of the mixture. When it is desired to have a rich mixture the ratio of gasoline to air is increased and when it is desired to have a lean mixture this ratio is decreased. In the drawings we have shown the preferred means of controlling this ratio. In this construction the air pipe 8 (see Figs. 3 and 5) is provided

with a valve 11 by means of which the air passing to the engine cylinders is controlled or regulated. Some means is provided for moving this valve to vary the amount of air passing to the engine cylinders. We prefer

to provide an arrangement by means of which this valve is moved by hand to restrict or decrease the amount of air passing to the engine cylinders and is then moved to increase the amount of air independent of the operator, this being done automatically when controlling handle is released. We have shown in the drawings one construction for this purpose. In this construction the valve 11 is pivoted at 12 at one side of the air pipe or

passageway. The end of this pivot projects out of the pipe and has connected therewith a controlling arm 13. The arm 13 is provided with a projecting end 13^a which projects beyond the shaft, 12, (see Fig. 3). This projection has connected with it a part 13^b which surrounds the pin 13^c through the center of the spring 53. This pin is carried

by a part 13^d connected with the shaft 12. When the valve 11 is opened, the spring 53 is compressed by the part 13^b sliding along the pin 13^c. This arm is connected with the link 14 which in turn is connected with an arm 15 attached to the rotatable part or shaft 16. The shaft 16 is provided at one end with a toothed part 17 (see Fig. 4) located in the casing 18, and which engages a rack 19 attached to an inner sliding part 20 which reciprocates within the casing 18. The reciprocating part 20 is provided with two valves 21, 22. The valve 21 controls an opening 23 in the valve chamber 24, and the valve 22 controls an opening 25 in the valve chamber 26. A spring 27 normally presses the valve 21 against its seat and a spring 28 normally presses the valve 22 against its seat. Spring 29 resists the movement of the reciprocating part 20 and normally tends to hold it at one end of the casing 18. The shaft 16 is rotated by means of a controlling member 30 (see Fig. 1) which is located in proximity to the driver, and which is preferably provided with an indicating part 31, which also acts as a thumb piece, and which when rotated, works over an indicating device 32 (see Fig. 2) which indicates the richness of the mixture. When the controlling device 30 is rotated it rotates the shaft 15 and through the members 15, 14, 13, and the shaft 12 moves the valve 11 to close the pipe 8 which conducts air to the carburetor. The valve 11 is preferably of spring metal so that when a current of air of sufficient force engages it it will open the amount desired. The rotation of the shaft 16 also rotates the tooth part 17 and lifts the rack and reciprocating device 20, moving it to the other end of the casing 18. When the controlling device 30 is released the valve 11 is gradually opened independent of the driver or operator. Any suitable means to secure this result may be used.

The viscosity of the fluid is changed in the proper ratio to the temperature, the engine or climatic temperature determining the rate of return, the colder the weather the longer it will be necessary to run on an enriched mixture and vice versa.

In the construction shown in Figs. 1 to 8 the casing 18 is provided with a suitable fluid or liquid, such for example, as oil of sufficient viscosity to delay the return of the part 20, and hence the opening of the valve 11 the desired amount. When the reciprocating part 20 is moved upwardly toward the opposite end in which it is shown in Fig. 4, the valve 21 is opened so as to let the liquid pass below the reciprocating part through the opening 33 (see Fig. 4), the valve 22 being closed by this liquid which enters the valve chamber through the opening 34. When the controlling device 30 is released, the spring 29 moves the reciprocating device 20 back to its initial position.

The oil is slowly by-passed around the check valves through a small hole 20^a, the speed being controlled by the viscosity of the fluid and the size of this hole. If the operator desires to return the valve 11 to normal position manually, this can be done by operating the controlling device 30 in the reverse direction, the additional pressure produced thereby opening check valve 22. The valve 22 is opened by the pressure of the liquid so as to let it pass through the opening 34 to the other side of said valve, and the valve 21 is closed by the pressure of the liquid during this movement.

We prefer to have the openings 23 and 33 larger than the openings 34 and 25, so that the reciprocating part 20 can be moved upwardly rapidly and will be moved downwardly at a much slower rate. The parts, of course, will be regulated to as to get the desired slowness of the downward movement to open the valve 11 at the desired time.

In the construction shown in Figs. 4, 7, and 7^a, the valves 21 and 22 are connected with a part 20^b which is removably attached to the reciprocating part 20 and which forms the piston in the cylinder. The part 20^b is shown separate from the part 20 in Fig. 7^a. We prefer to have an automatic device for quickly moving the parts 20 and 20^b when the engine cylinders are hot and it is not necessary to have the rich mixture. We have shown one construction for this purpose in Figs. 4, 7, and 7^a consisting of a device for automatically opening a passageway through the piston 20^b which shall be larger than the opening 20^a. In the construction shown this is accomplished by means of a thermostatic member 20^c which is looped over the member 20^b and fastened at one end by the fastening device 20^d. This thermostatic member has a projecting part 20^e which engages the end of a lever 20^f pivoted at 20^g. The lever 20^f is connected to the lever 20^h which is pivoted at 20ⁱ and which has a part 20^j which bears against the valve 21. When the cylinders of the engine become heated the oil in the cylinder 18 is heated and this heated oil causes the thermostatic member 20^c to move the levers 20^f and 20^h so as to open valve 21. This permits free movement of oil through the piston and causes the piston to descend quickly under the pressure of the spring 29. When the engine is cold the oil in the cylinder 18 will be cold and the thermostatic device will be moved so that the spring 27 will cause the valve 21 to be closed.

We have shown in Fig. 1 a priming device for priming the engine cylinders when starting.

We have illustrated the vacuum tank 36 which is connected by the pipe 37 with the source of fuel supply and by the pipe 38 with the carburetor 6, and by the pipe 39 with the manifold so that the vacuum can

be produced by the suction of the cylinders. We provide a priming pipe 40 which leads to the engine cylinders, and which is connected to the pump 41 in proximity to the driver, said pump being actuated by the handle 42. This pump is connected by pipe 43 with the fuel supply in the tank 36, the connection being made to the pipe 38 as shown. By actuating the pump a priming charge is inserted in the engine cylinders at the starting.

In Figs. 9 and 10 we have shown a modified construction wherein the controlling device for the valve 11 reciprocates instead of rotates. This controlling part 44 is directly connected with the reciprocating device 45 in the casing 46, so as to directly move the reciprocating device against the pressure of the spring 47. Connected with the con-

trolling part 44 is a controlling part 50 which is connected by a link 51 and a lever 52 with the shaft 12 of the valve 11 in the pipe 8. It will be seen that by this construction the valve is opened and the reciprocating part 45 in the casing 46 are simultaneously moved by a reciprocating motion. We prefer to provide the valve 11, in all instances, with a spring 53 which is compressed when the valve is closed and which also acts to give the valve elasticity and to permit its movement independent of the reciprocating parts 20 and 45, gradually reducing the tension on the valve 11. The part 13 is loosely mounted on shaft 12 and has a projection which is fastened to pin 35 surrounded with spring 53. The valve 11 is rigidly connected with the shaft 12, and there is a projection on the shaft connected therewith which has an opening through which pin of spring 53 passes. The spring 53 engages this projection. It will be seen that when the parts are actuated to move lever 13 upwardly (see Fig. 5) this pin will be moved downwardly to compress spring 53 between its head and the part connected with the valve, and this will cause the valve to move to its closed position, as shown in dotted lines. It will, therefore, be seen that this valve 11 is elastically connected both with the means for closing the valve and the means 50 for opening the valve.

In Figs. 9 and 10 we have also shown a construction wherein a liquid, such as oil, is used in the casing 46.

In Fig. 11 we have shown a construction where air is used to delay the opening of the valve 11. In this construction the casing 54 has the reciprocating device 55 which is connected to the controlling part 44. The controlling part is returned to its initial position by the spring 56. This controlling part is shown here as a piston with flexible packing rings 57. The end of the casing 54 is provided with the openings 58 and 59 which lead to the valve chambers 60 and 61, which have at 65 the lower end the openings 62, 63. Within the

valve chambers are the valves 64 and 65 normally pressed on their seats by the springs 66, 67. When the reciprocating part 55 is moved upwardly by the controlling part 44, the valve 65 is closed by the pressure of the air and the valve 64 opened so that air enters the casing 54 to permit this movement. When the reciprocating device is returned by the spring 56, the valve 64 is closed and the valve 65 opened to let the air out of the casing. The by-pass arrangement is similar to that shown in Fig. 7. The valves 64 and 65 and the openings to the valve chambers may be adjusted to secure a quick upward movement of the reciprocating part 55, and a properly delayed downward movement which causes the valve 11 to be opened after the proper interval.

We claim:

1. An internal combustion engine comprising cylinders, pistons in said cylinders, a carburetor connected with said cylinders, a communication between said carburetor and a source of fuel supply, an air inlet for said carburetor, a valve for controlling said air inlet, hand operated means for closing said valve and means capable of acting independent of temperature changes independent of the operator for opening said valve, said valve being elastically connected with both of said means.

2. An internal combustion engine comprising cylinders, pistons in said cylinders, a carburetor connected with said cylinders, a communication between said carburetor and a source of fuel supply, an air inlet for said carburetor, a valve for controlling said air inlet, hand operated means for closing said valve and means independent of the operator for opening said valve, said means capable of acting independent of temperature changes comprising a casing, a reciprocating part in said casing operatively connected with said valve so as to close it when moving in one direction, and means for automatically moving the reciprocating device in the other direction, two oppositely acting valves, one adapted to be actuated by said reciprocating part when it is moved in one direction, and the other adapted to be actuated by said reciprocating part when it is moved in the other direction.

3. An internal combustion engine comprising cylinders, pistons in said cylinders, a carburetor connected with said cylinders, a communication between said carburetor and a source of fuel supply, an air inlet for said carburetor, a valve for controlling said air inlet, hand operated means for closing said valve and means independent of the operator for opening said valve, said means capable of acting independent of temperature changes comprising a casing, a reciprocating part in said casing operatively connected with said valve so as to close it when moving in

- one direction and means for automatically moving the reciprocating device in the other direction, two oppositely actuated valves, one adapted to be actuated by said reciprocating part when it is moved in one direction and the other adapted to be actuated by said reciprocating part when it is moved in the opposite direction, said reciprocating part being provided with a small opening independent of either of said valves, and means for retarding the automatic movement of said reciprocating device.
4. An internal combustion engine comprising cylinders, pistons in said cylinders, a carburetor connected with said cylinders, a communication between said carburetor and a source of fuel supply, an air inlet for said carburetor, a valve for controlling said air inlet, hand operated means for closing said valve and means independent of the operator for opening said valve, said means comprising a casing, a piston therein, means for permitting the piston to move rapidly in one direction comprising a large valve controlled opening with a movable valve associated therewith, an elastic device for pressing said valve towards its closed position and a thermostatic device for moving said valve towards its open position when the temperature in the casing reaches a predetermined point.
5. An internal combustion engine comprising cylinders, pistons in said cylinders, a carburetor connected with said cylinders, a communication between said carburetor and a source of fuel supply, an air inlet for said carburetor, a valve for controlling said air inlet, hand operated means for closing said valve and means capable of acting independent of temperature changes independent of the operator for opening said valve, and means independent of the suction of the cylinders for injecting an initial charge of fuel supply into said cylinders.

Signed at Chicago, Illinois, this 4th day of June, 1925.
